United States Patent Office

Des. 222,406
Patented Oct. 19, 1971

222,406

HANDBAG OR THE LIKE

Benjamin Krifchin, Baltimore, Md., assignor to General Crafts Corporation, Baltimore, Md.

Filed Aug. 4, 1970, Ser. No. 24,297

Term of patent 3½ years

Int. Cl. D3—02

U.S. Cl. D87—3

FIG. 1

FIG. 2

FIG. 3

FIG. 4

FIG. 5

FIG. 1 is a front elevation of a handbag or the like showing my new design;

FIG. 2 is a rear elevation thereof;

FIG. 3 is an end elevation taken from the right in FIG. 1;

FIG. 4 is a plan view thereof; and

FIG. 5 is a bottom view thereof.

I claim:

The ornamental design for a handbag or the like, substantially as shown.
